(57) **CLAIM**

The ornamental design for an air freshener, as shown and described.

DESCRIPTION

1. Air freshener
- 1.1 : Front
- 1.2 : Perspective
- 1.3: Left
- 1.4: Right
- 1.5 : Back
- 1.6 : Back

The design consists of an air freshener comprising a stand, and a wick that can be impregnated with volatile substances, extending through and attached to the stand, and an anchoring element which connects to the wick and the stand; figure 1.1 is a front view of the design for which protection is sought; figure 1.2 is a perspective view thereof; figure 1.3 is a side view thereof; figure 1.4 is a side view thereof; figure 1.5 is a rear perspective view thereof; figure 1.6 is a rear view thereof.
